SALAD HANDLING IMPLEMENT OR THE LIKE

Joseph B. Stier, New York, N. Y.

Application June 19, 1956, Serial No. 41,964

Term of patent 14 years

(Cl. D44—29)

Fig. 1.

Fig. 2.

Fig. 3.

Fig. 1 is a top plan view of a salad handling implement embodying my new design;

Fig. 2 is an edge view of the same; and

Fig. 3 is an end view of the same.

I claim:

The ornamental design for a salad handling implement or the like, substantially as shown.
